(57) **CLAIM**

The ornamental design for a bottle, as shown and described.

DESCRIPTION

FIG. 1 is a front and side perspective view showing a first embodiment of a bottle showing my new design;

FIG. 2 is another perspective view of the bottle from FIG. 1; FIG. 3 is another perspective view taken from underneath the bottle from FIG. 1;

FIG. 4 is a front elevation view of the bottle from FIG. 1, the rear elevation being a mirrored view thereof;

FIG. 5 is a side view of the bottle from FIG. 1, the opposite side being a mirrored view thereof;

FIG. 6 is a top plan view of the bottle from FIG. 1;

FIG. 7 is a bottom plan view of the bottle from FIG. 1;

FIG. 8 is a perspective view showing a second embodiment of a bottle showing my new design;

FIG. 9 is another perspective view of the bottle from FIG. 8; FIG. 10 is another perspective view taken from underneath the bottle from FIG. 8;

FIG. 11 is a front elevation view of the bottle from FIG. 8, the rear elevation being a mirrored view thereof;

FIG. 12 is a side view of the bottle from FIG. 8, the opposite side being a mirrored view thereof;

FIG. 13 is a top plan view of the bottle from FIG. 8;

FIG. 14 is a bottom plan view of the bottle from FIG. 8;

FIG. 15 is a perspective view showing a third embodiment of a bottle showing my new design;

FIG. 16 is another perspective view of the bottle from FIG. 15;

FIG. 17 is another perspective view taken from underneath the bottle from FIG. 15;

FIG. 18 is a front elevation view of the bottle from FIG. 15, the rear elevation being a mirrored view thereof;

FIG. 19 is a side view of the bottle from FIG. 15, the opposite side being a mirrored view thereof;

FIG. 20 is a top plan view of the bottle from FIG. 15; and,

FIG. 21 is a bottom plan view of the bottle from FIG. 15. The broken lines shown in FIGS. 1-6, 8-13, and 15-20 show portions of the bottle that form no part of the claimed design.
